JOHN P. CASE, OF CHICAGO, ILLINOIS, ASSIGNOR TO THE BROWN HOISTING MACHINERY COMPANY, OF CLEVELAND, OHIO, A CORPORATION.

STORAGE BIN.

Application filed June 7, 1922. Serial No. 566,526.

To all whom it may concern:

Be it known that I, JOHN P. CASE, a citizen of the United States, residing in the city of Chicago and State of Illinois, have invented 5 a new and useful Storage Bin, of which a full, clear, and exact description is herein set forth as follows, namely:

The invention belongs to that class of bins and receptacles, that are chiefly employed in 10 the making and repairing of roads, pavements, sewers and the like, wherein stone, gravel, sand, cement and similar material, are to be contained and drawn off from, for use at successive points along an extended 15 course or line of construction.

From the nature of things, a structure of 20 the kind, should have a low original cost that is not out of proportion to the cost or contract prices of the work to which it is to be applied, and be organized with a view to its 25 ready erection and re-erection in the field, and the prompt repair and replacement, when required, of all parts that are subject to wear and injury in the use.

Heretofore, so far as known, apparatus of 30 this class, have been either all-wood or all-steel.

The all-wood is the obvious form for those 35 who emphasize the importance of a low first cost and immediate availability, inasmuch as the material for such form is light, at hand, and is easily worked up. In consequence, the design and construction of this type, is generally hurried and according to rule of thumb methods, with the result that 40 more material is used in the construction than the actual strains and stresses require, and the bin itself is invariably built up at the site for operation, by fastening the parts in place with spikes or other conjoinable means.

Aside from being cumbersome, and unscientific in build, a wooden bin of this description, is necessarily expensive in use and 45 short-lived, because, in the process of dismantling the same for each new erection along a given job, all pieces must be forced apart by crow-bars or other wrecking implements, whereby such parts are so damaged as

to require frequent replacements and repairs, and the bin itself is soon rendered valueless.

The all-steel bin, on the other hand, although more lasting, is the more expensive, not only in its first cost but in its mode of use. Such may be referred to as fabricated bins, since they are made up of definite riveted sections to be bolted together for the completed unit. By reason of this characteristic, the weight of the sections to be handled in the field and transported from time to time, largely impedes the essential operations of dismantling and re-erecting, and adds to both the cost and the time of such operative movements.

It is the primary purpose of the present invention, therefore, to meet the conditions above indicated, by supplying a bin-form of a knock-down construction or character, in which the principal parts are of wood, are 70 scientifically laid out, and adapted to be adjustably connected to each other without the aid of spikes or other destructive means.

In the drawings, Figure 1 is a side elevation of a primary or single bin of one-panel 75 length. Figure 2, is an enlarged view of a portion of the upper part of the bin, showing the girder member in its relation to the same. Figure 3, is a section on the line *a*, *a*, of Fig. 2. Figure 4 is a side elevation of a 80 secondary unit or panel, ready for combination with a single or primary unit or panel, or with one of a series of such units. Figure 5 illustrates a rod-bolt for a single unit, when the same is adapted for use with a 85 double-panel as shown in Fig. 4. Figure 6 is a side elevation of a unitary combination of a primary and a secondary unit. Figure 7 is a plan view of Fig. 6. Figure 8 is an end view of either Fig. 1 or Fig. 6, and 90 Figure 9 is a modified form of a bin-end anchorage.

The storage bin, as constructed in Figs. 1 and 8, is a single-panel or unit, made up of a rectangular supporting frame-work 95 composed of posts 10, at each corner, resting on two oppositely placed sills 9, 9. The posts are sustained, in their upright positions, by

overlapping timbers 11, 11, that are bolted to the sill and post in each case. They are further held together and braced, in the direction of the sills, by diagonal cross-
5 braces 12—12, and horizontal braces 12^a, and, in the transverse direction, by similar bracing members 14—14, and 14^a.

Across and resting upon the tops of each 10 pair of transversely related posts 10, is a tie or cross-timber 13, which is held in place by an over-lapping timber 13^a that is bolted to the cross-timber and post to be secured.

Said tie-timbers 13, are notched near their 15 ends, directly above the posts, in a manner to form shoes or bearings for the ends of the bin-supporting timbers 15, 15, at right angles to the line of stress produced by the bin-body proper in the completed structure.

The girder-members 15, 15, are each made 20 up of a pair of equidimensional beams or timbers 15^a, 15^a, adapted to be bolted together through their entire length. They should be of such length that, when in their stated places on the posts, they will span the 25 panel and extend to the center line of their supporting posts.

In practice, the beam members 15^a should not be bolted together into the girders 15, until, having been loosely laid in their 30 designed places on the tie-timbers, the ends of a series of downwardly extending substantially parabolic shaped bars, or straps 16, in spaced apart relations to each other, have severally been brought between the same, and anchored or otherwise secured against 35 retraction, at the upper side of the beams 15. This may be effected in any suitable manner, and, as shown in the drawings, is provided for by a pair of oppositely related steel angles 17, 17, along the top of each girder 15, that are adapted to be drawn together against the intervening straps 16, by the common bolts 17^a, 17^b when passed through holes provided in the three parts for the purpose.

40 The timbers 15^a, 15^a, may now be bolted together by bolts indicated by 15^b and the frame of the bin-body will be ready for its characteristic form of lining. This lining consists and is made up of a series of scantling-like piece-members 18, preferably of 45 two-by-four inch timber, of the same length as the girders 15, arranged longitudinally side by side, with a longer side or face of each in bearing with the bars or straps 16, and cross-wise of the same throughout their 50 length.

In order to hold the numerous pieces in 60 place, secondary straps, or bin-lining retainers 19—19, of parabolic shape, are applied, at intervals, to the bin-lining B when made up as described, and fastened in such position by bolts 20 that are passed through holes in the straps and lining for the purpose.

65 Downwardly extending closure-pieces 21,

of the same parabolic outline and area as the straps or loops 16, are fitted between and across the open spaces at the ends of the series of piece-members 18, in order to thereby close and complete the bin-body B. The 70 pieces 21 may be fastened at their tops to the inner sides of the cross-timbers 13—13, and be reinforced in their positions, by cross-timbers 21^a, 21^b, arranged transversely of the exterior faces of the timbers 21, and with their ends projecting laterally through the bin-body B. Said ends may there be engaged by rod-bolts 22, 22, that are adapted to extend between and tie the pairs of projecting cross-timbers 21^a and 21^b at each 75 80 side of said body.

Inasmuch as, in the figures, the series members 18 extend beyond the end-pieces 21, certain of the pieces must necessarily be shortened, as is shown, in order to leave a 85 space for said reinforcing timbers 21^a and 21^b.

A chute 23, a chute-opening 23^a, and a gate 24, are shown in the figures as connected to the bin-bodies B.

Certain of the figures also indicate how the bin as constructed in a single panel form, or when extended into a unit of several panels, may be further enlarged by the 90 addition of other panels.

This may be effected in the structures already described, by removing an end-piece 21, and the frame braces 14, 14, across that end, and boring holes in the posts 10, at the point indicated by 10^a, for bolting thereto 100 the cross-brace 12^a of the panel to be annexed, and holes in the sills 9, at 9^c, for connecting up to the same, splicing timbers 9^b, on the ends of the sills 9^a of the portion of the bin that is to be annexed. Extra holes 105 17^a, should be punched in the ends of the angles 17, which, of course, may best be done when the angles are prepared for their use generally with said storage bin.

Prolongation-bars 25, are provided with 110 holes therein spaced by the established distance between the holes 17^a of the angles 17.

By these means, as will be obvious, the second panel-unit is connected to the first, the bars 25 holding the panels together at 115 the top, the braces 12^a at the center of the posts, and the splicing timbers 9^b at the sills. The bin-end 21, and the bracings that were removed from the original panel, are used at the open end of the second panel. As 120 illustrated in Fig. 5, in order to utilize the rod-bolts 22, for tying the end timbers 21^a and 21^b in their respective places, and holding the panels together at the seam S, sleeve-nuts 26 may be screwed onto the rod-bolts 125 22, to receive the ends of a shorter rod-bolt 22^a, of a suitable length, in combination with the rod 22 and said sleeve, to answer for the purpose. Extensions 21^a, Fig. 4, may be provided to fill the spaces vacated by 130

the timbers 21^a and 21^b, when the described enlargement of an original single-panel bin is made.

When it is desired to install an original unit of two-panels, the construction is somewhat varied from that when an addition merely, is made to a one-panel unit as a nucleus. In the former case, the sills are not formed by splicing, but, as also are the horizontal bracings, the girder timbers at the top of the frame, and the bin-lining members, are continuous through their entire course, so that longer single parts 27, 28, 29, and 31, severally take the places of the sills 9 and 9^a, and extension pieces 9^b and 25, the horizontal bracings 12^a, the series members 18, and the girder timbers 15.

Inasmuch as, in the form last considered, there will be no break or seam in the series of timbers that make up the bin-lining, the rod-bolts 22 and 22^a, may be dispensed with, and a form of bin-end anchorage used instead as shown in Figs. 6 and 7, wherein a steel bar 30, bent at one end, and having a right-angled leg 30^a, is fastened to the outer side of the bin with bolts that engage the straps 16. The legs 30^a are in bearing with and are bolted to the projecting ends of the timbers 21^a and 21^b.

Although the foregoing describes a storage bin construction that combines a minimum of weight with the fullest strength demanded, and wherein the major parts are all detachably connected in their places with the view of permitting the construction, as a whole, to be speedily set up or knocked down, as occasions demand, it is plain that the bin-body feature alone of the construction, without regard to the supporting frame therefor, is a sufficiently novel and useful embodiment of the same structural rule and purpose, to entitle it to be specifically claimed in the present application, and such claims are presented accordingly.

The bodies or body linings of all receptacles for grosser materials like coal, sand, limestone, etc., are necessarily subject to a more or less rapid wear and destructive use, but the peculiar course or strip formation devised in the present case, by enabling the entire body or lining, or any part or portion thereof, when outworn or damaged, to be quickly removed and replaced by inexpensive ready-for-use material or parts, favorably differentiates the construction from others of the kind.

It is further to be observed that, in describing the invention herein, it is not intended to limit the same, in all cases, to the strict significance of the words employed. When, for instance, the shape of the bin-straps, or bars, is specified as parabolic, any upwardly flaring support will equally serve, that permits the series of strips, or members 18, to be arranged thereon with one side in

bearing with the support, and its adjacent side or sides in close juxtaposition with the next member or members of the series. So, too, the timber-members 18, though recited as continuous, are not necessarily homogeneous, but may be interrupted, for example, so as to leave openings for discharge chutes, and, also, may be composed of several shorter pieces arranged end to end.

What I claim, and wish to secure by Letters Patent is:—

1. A knockdown storage bin made up of the combination of a supporting frame, oppositely related bin-sustaining girders mounted thereon, a series of downwardly extending substantially parabolic-shaped bar-members removably suspended from said girders, and a series of scantling-like members, fastened together side by side, upon the bottom and sides of said bar-members and cross-wise of the same, substantially as shown and described.

2. As a unitary construction, a knockdown storage bin, comprising the combination of a supporting frame made up of ready for use parts removably fixed in their places, a bin-member suspended from said frame by a series of substantially parabolic-shaped bars, detachably connected at their ends to the frame, a bin-lining composed of a series of wooden strips arranged cross-wise of said bars, and retaining-straps arranged at intervals cross-wise of said series of strips and bolted to the same, substantially as shown and described.

3. As a unitary construction, a knockdown storage bin, comprising the combination of a supporting frame made up of ready-for-use parts removably fixed in their places, oppositely related girder-members across the top of said frame, a series of downwardly extending substantially parabolic-shaped bar-like members, detachably connected at their ends to said girder-members, a series of equidimensional wooden strip-like members upon the upper side of the series of bar-like members, means for removably retaining said series in said described relation to each other, and closure-members across the ends of said series of strips, substantially as shown and described.

4. In a knockdown storage bin and like receptacle, the combination, with a suitable base or anchorage, of a series of downwardly extending substantially parabolic-shaped bars detachably sustained thereby, and a bin-body, having its bottom and sides formed of a series of closely arranged equidimensional strips of wood, upon and supported by said bars, and removably held in said relation by means suitable for the purpose, substantially as shown and described.

5. In a storage bin, and like receptacle, the combination, with a suitable base or anchorage, of a series of downwardly extending

substantially parabolic-shaped bars sustained thereby, a bin-body having its bottom and sides formed by successive courses of longitudinally arranged wooden strips, each 5 member of said courses having one side thereof in bearing with said bars, and, the next adjacent sides thereof, in bearing, respectively, with corresponding sides of ad-

joining members of said course, and suitable means of detachably securing the same in 10 said position, substantially as shown and described.
